United States Patent Office.

JOHN HOUP, OF SPRINGTOWN, PENNSYLVANIA.

Letters Patent No. 90,542, dated May 25, 1869.

IMPROVEMENT IN STEAM-ENGINE CONDENSERS.

The Schedule referred to in these Letters Patent and making part of the same.

To all whom it may concern:

Be it known that I, JOHN HOUP, of Springtown, county of Bucks, State of Pennsylvania, have invented certain Improvements in Condenser for Steam-Engines; and I do hereby declare the following to be a full, clear, and exact description of the same.

My invention consists of certain improvements, fully described hereafter, in condensers and valves, to be used in connection with the steam-engine for which Letters Patent were allowed to me on the 19th day of February, A. D. 1869.

In order to enable others skilled in the art to make and use my invention, I will now proceed to describe its construction and operation, reference being had to the accompanying drawing, which forms a part of this specification, and in which—

Figure 1 is a vertical sectional view of sufficient of a steam-engine to illustrate my improvements;

Figure 2, a sectional plan view of the same, on the line 1-2, fig. 1; and

Figure 3, a section on the line 3-4, fig. 1.

The condensing-apparatus represented in the drawing consists of a casing of thin metal, the interior of which is divided by a partition, *b*, into two compartments, *A* and *A'*, the former of which is merely a steam-reservoir, while the latter and largest compartment forms the condenser proper.

Exhaust steam from the engine is admitted into the compartment *A* through a pipe, *B*, provided with a valve, *C*, which forms an important part of my invention, and will be fully described hereafter; and at the top of the compartment *A* is a safety-valve, *b'*, of ordinary construction, for permitting the escape of steam from the said compartment, should it at any time become overcharged.

A number of horizontal tapering tubes, *D*, contained entirely within the compartment *A'* of the condenser, is secured to the partition *b*, in such a manner that they shall communicate with the interior of the compartment *A*, and each of the said tubes is perforated with small holes throughout the entire length, and is provided, at its outer end, with a perforated bulb or rose, *c*.

F F F are rows of vertical tubes secured to the top of the condenser, and projecting downward into the compartment *A'* of the same, between and on each side of the rows of horizontal tubes *D*. These tubes *F* are open at their upper ends, but should be wholly or in part closed at the bottom, and all of them are perforated with small holes throughout their entire length, in the same manner as the tubes *D*.

h h' h² are vertical plates, so arranged within the compartment *A'* that they shall direct currents of air and steam through the same in a circuitous course, as hereafter described; and extending between the plate *h'* and partition *h*, at a point beneath the pipes *D*, is

an inclined partition, *i*, provided with an opening, covered by a valve or damper, *j*, operated from without the apparatus by a rod, *j'*. (See fig. 1.)

At the top, and at one end of the compartment *A'*, is arranged an exhausting-fan, *G*, and at the bottom of the said compartment are pipes, *m*, *m'*, and *m²*, for carrying off the water of condensation, &c., as hereafter explained.

The operation of the condenser is as follows:

Motion being communicated to the fan *G*, a partial vacuum is produced within the apparatus, causing air to enter at the upper ends of the tubes *F*, and to pass through the perforations of the same, in numerous small jets, the whole forming a current, which is directed, by the plates *h*, *h'*, and *h²*, in the course of the arrows, fig. 1, towards the fan.

The exhaust steam first enters the compartment or receiver *A*, where its pressure is somewhat equalized, and passes thence into the compartment *A'*, through the horizontal tubes *D*, it issuing from the perforations of the latter, and from the roses or bulbs *c* of the same, in numerous small jets, and becoming thoroughly commingled with the jets of cold air from the tube *F*, by which it is rapidly condensed.

The partitions or deflecting-plates *h*, *h'*, and *h²*, cause the combined air and steam to take the circuitous course before described, so that the greater portion of the steam may become condensed, and fall to the bottom of the apparatus, before the currents reach the fan, and are expelled by the same through the discharge-pipe *g*.

The object of the partition *i*, beneath the pipes *D*, is to prevent the hot steam, as it emerges from the latter, from coming in contact with and vaporizing the condensed-steam water at the bottom of the apparatus; and the valve *j*, which can remain partially open, permits the escape of any water which may accumulate upon the said partition.

The condensed-steam water is drawn off, from time to time, through the pipe *m*, and may be used as feed-water for the boiler, and the overflow-pipe *m'* prevents more than a certain quantity of water to accumulate in the apparatus, if it should not be drawn off through the pipe *m*.

In the steam-engine for which Letters Patent were allowed to me on the 19th day of February, 1869, a method was described for effectually condensing high-pressure exhaust steam, by passing it into two condensers instead of one, as heretofore.

The first condenser was to receive all of the exhaust steam above a certain pressure, when a valve was closed, and a second condenser permitted to exhaust the remainder of the steam, and to produce the required vacuum in the steam-cylinder.

My present invention is intended principally to be used in connection with the above arrangement, for

receiving and condensing the first portion of the exhaust steam, the valve C in the supply-pipe forming, in this case, an important adjunct.

The valve is operated by a bell-crank lever, n, connected to the slotted end of a rod, o, which receives its motion from an eccentric on the main shaft of the engine, and a spring, t, bearing against the lower arm of the lever n, has a constant tendency to retain the valve upon its seat.

The valve is operated by means of the rod r, at the moment exhaust steam is to be passed into the condenser, and when the pressure of the steam has been sufficiently reduced, the valve is closed by means of the spring t, (the end of the eccentric rod being slotted, as above mentioned, to permit this independent action of the spring.)

My object in thus operating the valve is to prevent it being closed before the pressure of the steam is sufficiently reduced, which might occur if the valve was operated by the rod alone.

I claim as my invention, and desire to secure by Letters Patent—

1. A casing, into which project perforated tubes D, through which steam is discharged, and perforated pipes F, communicating with the external air, substantially as described.

2. The arrangement of the compartments A and A', perforated tubes D and F, and fan G, the whole being constructed substantially as set forth.

3. The combination of the compartments A and A', tubes D and F, and inclined partition i, substantially as herein described.

4. The valve C, operated by a bell-crank lever, r, slotted eccentric rod s, and spring t, substantially in the manner set forth.

In testimony whereof, I have signed my name to this specification, in the presence of two subscribing witnesses.

JOHN HOUTP.
